LEE R. TITCOMB, OF BROOKLYN, NEW YORK.

DRIVING UNIT FOR LOUD-SPEAKERS

Application filed December 17, 1927. Serial No. 240,845.

My invention relates to a new and improved driving unit for loud speakers.

One of the objects of my invention is to provide a driving unit to which a large amount of energy can be supplied and which will be substantially distortionless.

Another object of my invention is to provide a driving unit which employs a magnet having a minimum of residual permanent magnetism.

Another object of my invention is to produce a driving unit in which distortion is minimized.

Other objects of my invention will be set forth in the following description and drawings which illustrates a preferred embodiment thereof, it being understood that the above general statement of the objects of my invention is intended merely to generally explain the same and not to limit it in any manner.

Fig. 1 is a diagrammatic view illustrating the general principle of my invention.

Fig. 2 shows an embodiment thereof in
25 more efficient form.

Fig. 3 is an end view of Fig. 2.

As shown in Fig. 1 the unit is provided with a magnet core 1 which is preferably made of silicon steel, which has little or no residual magnetism so that said core 1 does not pro-

30 magnetism so that said core 1 does not produce any magnetic flux save when a current is passed through what may be termed the field coil 2 thereof. The output circuit from the radio receiving set or any other source of 35 electric current modulated to correspond to the sound to be amplified, is connected to the

the sound to be amplified is connected to the field coil 2. The field coil 2 has a secondary coil 3, which has preferably fewer turns than the primary coil 2, so that the voltage in the secondary coil 3 is lowered. The secondary coil 3 is connected to what may be termed the actuating coil 4 which is wound around the

45 armature 6. The armature 6 is pivotally connected at 7 to the core 1 and its outer end is connected to the rod 8 which is suitably connected to the diaphragm, tympanum, or other member to be vibrated.

The armature 6 is also preferably made of silicon steel for the reason above mentioned.

60 It is obvious that when a varying current is

fed to the primary coil 2 that a corresponding alternating current is produced in the actuating coil 4 so that the free end of the armature 6 has its magnetic polarity changed in accordance with the change of the current in the actuating coil 4. The current which is supplied to the coil 2 from the ordinary receiving set consists of a direct current component and a superposed pulsating current component. However, the current which is supplied to the coil 2 is not an alternating current so that the magnetic flux produced thereby in the core 1 never has its direction reversed. That is, the flux passing between the ends or pole pieces of the core 1 changes in value but the said flux always passes in the same direction. The current induced in the secondary coil 3 is produced solely by the fluctuating component of the current supplied to the coil 2. Hence, a pure alternating current of variable magnitude is induced in the secondary coil 3 and this is supplied to the actuating coil 4. As the direction of the current in the actuating coil 4 is reversed, the polarity of the free end of the armature 6 is also reversed. However, the current which is ordinarily fed to the coil 2 has a direct current component which is much larger than the pulsating component. For example, a typical current which is fed to the coil 2 has a direct current component of about 20 milliamperes while the fluctuating current component does not exceed about $\frac{1}{2}$ milliamperes.

By properly regulating the length of the air gap of the core 1 so that the direct current component of the current fed to the coil 2 magnetizes the core 1 a little below the saturation point, the flux passing across the air gap of the core 1 can be caused to remain substantially unaffected by the pulsating component of the said current supplied to the coil 2. Hence, the movement of the armature 6 is proportional to the value of the pulsating current component fed to the coil 2. 95

By using an electro-magnet in the driving unit, a much greater flux can be secured than is possible with the permanent magnets which are now commonly utilized. For example, by employing the electro-magnet above de-

scribed, it is possible to get a flux of from fifteen to twenty thousand gausses. An even more important advantage is the elimination of the direct current component from the actuating coil 4, without the use of choke coils, condensers, or the like, so that it is not necessary to use the so-called output transformer in the ordinary receiving set, because the unit constructed according to my invention has all the effect of this output transformer, as it is in effect the combination of an output transformer and a driving unit.

In the embodiment shown in Fig. 2, a core 9 made of silicon steel is provided with air gaps 10 and with openings 11 in which a primary coil 12 is located. A secondary coil 14 is associated with the said primary coil 12 and this is connected to a movable actuating coil 15, connected to a stirrup 16 which is connected at 17 to the diaphragm or tympanum 18. The diaphragm or tympanum 18 is suitably supported so as to normally hold the coil 15 in the position shown in Fig. 2. However, if an alternating current is supplied to the actuating coil 15, in the manner before described, said coil 15 will move up and down, thereby actuating the diaphragm 18.

The actuating coil 4 shown in Fig. 1 may be stationary and have sufficient internal diameter to permit the armature 6 to freely vibrate. However, the said coil 4 may be wound upon and may be movable with the armature 6 in which case the connections between the coils 4 and 3 are made sufficiently long and flexible to permit the free vibration of the armature 6.

While, as before stated, I prefer to use a magnet core which is preferably not permanently magnetized, the use of a permanent magnet would not be departing from the invention, which is operative if a permanent magnet is utilized.

I have shown a preferred embodiment of my invention, but it is clear that numerous changes and omissions could be made without departing from its spirit.

I claim:

1. A method of operating the movable member of an acoustic reproducer by means of an electric current having a relatively large direct current component and a relatively small pulsating current component, which consists in causing the said direct current component to produce a magnetic field having a fixed direction, causing the pulsating current component to induce a corresponding alternating current, and causing the magnetic flux produced by said induced alternating current to react with the magnetic field to operate said movable member.

2. An electro-magnetic driving unit for the movable member of a sound reproducer, comprising a magnet containing a field coil associated therewith, a secondary coil associated

with the said field coil so that the flux produced in said field coil by a fluctuating current passing through the same induces a secondary current in said second coil, and a third coil connected to the said second coil and adapted to cause the operation of said movable member.

3. An electro-magnetic driving unit for the movable member of a sound reproducer, comprising a magnet containing a field coil associated therewith, a secondary coil associated with the said field coil so that the flux produced in said field coil by a fluctuating current passing through the same induces a secondary current in said second coil, and a third coil connected to the said second coil and adapted to cause the operation of said movable member, the third coil being movable under the influence of the varying magnetic field produced by the said currents.

In testimony whereof I affix my signature.
